United States Patent Office

Des. 186,627

Patented Nov. 10, 1959

186,627

TUMBLING FINISHING MACHINE

Roy T. Romine, Vicksburg, Mich., assignor to Wheel-
abrator Corporation, Mishawaka, Ind., a corporation of
Nebraska

Application January 28, 1958, Serial No. 49,434

Term of patent 14 years

(Cl. D55—1)

Des. 186,627

PAGE 2

Figure 1 is a perspective view of the tumbling finishing machine embodying the new design.

Figure 2 is a perspective view of said tumbling finishing machine with the casing cover moved to expose the tumbling barrel.

Figure 3 is a rear elevational view of said tumbling finishing machine.

Figure 4 is an end elevational view of said machine at the drive end thereof.

Figure 5 is an end elevational view of said machine at the opposite end thereof.

I claim:

The ornamental design for a tumbling finishing machine, as shown.
